Attorney.

UNITED STATES PATENT OFFICE.

JEREMIAH KELLEHER, OF ERIE, PENNSYLVANIA, ASSIGNOR TO CONTINENTAL RUBBER WORKS, OF ERIE, PENNSYLVANIA, A CORPORATION OF PENNSYLVANIA.

RUBBER MAT.

1,401,788.

Specification of Letters Patent. Patented Dec. 27, 1921.

Application filed January 26, 1921. Serial No. 439,984.

To all whom it may concern:

Be it known that I, JEREMIAH KELLEHER, a citizen of the United States, residing at Erie, in the county of Erie and State of Pennsylvania, have invented new and useful Improvements in Rubber Mats, of which the following is a specification.

The mat is designed for use in such positions as the running board of an automobile. Where so placed it must be secured and it is also subjected constantly to changes in the weather. In carrying out my invention I reinforce the mat with a fabric, this forming a preferable means of reinforcement. The mat is provided with securing perforations which are reinforced, the fabric reinforcing the rubber sufficiently to make a secure attachment by means extending through the perforations. With such mats the moisture which is retained under the mat tends to destroy the mat. One of the features of my invention is the provision of ribs by means of which ventilation is provided below the mat and the mat stiffened.

The invention is illustrated in the accompanying drawings as follows:—

Figure 1 shows a plan view of the mat.

Fig. 2 a view of the bottom of the mat.

Fig. 3 a section on the line 3—3 in Fig. 1.

1 marks the support, as a running board,

and 2 the mat. The mat is provided with the reinforcing fabric 3, preferably in the form of duck, which is vulcanized in the rubber as the mat is formed. Perforations 4 are also formed in the rubber as it is vulcanized through which means may be extended for securing the mat in place. The mat is provided with the ribs 5 on its upper surface to give it an abrasive action and the ribs 6 are arranged on its under surface 40 preferably crosswise of the mat affording ventilation by means of the spaces 7. I preferably arrange a closing rib 8 along each edge. This keeps out some of the moisture but does not seal the spaces so as to prevent 45 the drying of the space under the mat.

The ribs further tend to stiffen the mat so that it lies flat on a running board. It is preferable to arrange the ribs on the upper surface so as to cross the ribs on the lower 50 surface, thus stiffening it in both directions.

What I claim as new is:—

A rubber mat having ribs on its upper and lower surfaces, the ribs on the lower surface being arranged transversely to the ribs 55 on the upper surface.

In testimony whereof I have hereunto set my hand.

JEREMIAH KELLEHER.
